VALVE UNIT FOR INFLATING LIFE RAFTS OR THE LIKE

Theodore N. Hannant, Cedar Grove, N. J., assignor to Specialties Development Corporation, Belleville, N. J., a corporation of New Jersey

Application November 9, 1949, Serial No. 5,939

Term of patent 14 years

(Cl. D78—1)

To all whom it may concern:

Be it known that I, Theodore N. Hannant, a citizen of the United States, residing in Cedar Grove, in the county of Essex, in the State of New Jersey, have invented a new, original, and ornamental Design for a Valve Unit for Inflating Life Rafts or the like, of which the following is a specification, reference being had to the accompanying drawing, forming a part thereof.

Figure 1 is a front elevational view of a valve unit for inflating life rafts or the like, embodying my new design;

The essential features of my design reside in the portions shown in full lines.

I claim:

The ornamental design for a valve unit for inflating life rafts or the like, substantially as shown and described.

THEODORE N. HANNANT.
